FIG. 5.

INVENTOR

Harry W. Falconer,
By *Curran Curran & Crampton*,
His attorney.

UNITED STATES PATENT OFFICE.

HARRY W. FALCONER, OF NEAR PERRYSBURG, OHIO.

BLOCK-UNITING MEANS.

Application filed August 30, 1920. Serial No. 407,023.

To all whom it may concern:

Be it known that I, HARRY W. FALCONER, a citizen of the United States, and a resident of the county of Wood, and State of Ohio, 5 near Perrysburg, Ohio, have invented a certain new and useful Block-Uniting Means; and I do hereby declare the following to be a full, clear, and exact description of the invention, such as will enable others skilled in the art to which it 10 appertains to make and use the same, reference being had to the accompanying drawings, and to the characters of reference marked thereon, which form a part of this 15 specification.

This invention relates to means for attaching blocks together, and has for its object the provision of a simple and efficient means of this character intended more particularly for use in securing together license 20 or serial number blocks of automobiles in a manner to render it extremely difficult to sever the connection between the blocks and change the numbers or arrangement thereof 25 without detection.

The invention is fully described in the following specification, and while, in its broader aspect, it is capable of embodiment in numerous forms, two preferred embodiments thereof are illustrated in the accompanying drawings, in which,

Figures 1 and 3 are side views of sets of number blocks secured together by different forms of the invention and with parts 35 broken away. Figs. 2 and 4 are end views respectively, thereof, and Fig. 5 is a different side elevation of a portion of the blocks shown in Fig. 3 with a part in section.

Referring to the drawings, 1 designates 40 individual blocks preferably of glass, porcelain or other ceramic material and bearing a designation mark thereon such as a numeral, letter, or the like, so that a number or word or series of numbers or words may 45 be built up by placing a plurality of such blocks bearing desired designations side by side.

The purpose of the invention is to secure 50 a plurality of such blocks together in assembled form in a rigid and secure manner, and this is accomplished by providing holes 2 through the blocks in longitudinal register one with another, so that a binding material may be poured therethrough, such material

being of a nature to adapt it when hardened 55 to form a rigid connecting or uniting means 3 for the blocks. The binding means 3 may be of metal or other suitable material, capable of being poured or deposited in the aligned openings 2 in a molten or fluid state 60 and then to harden when cooled.

In order that the binding means may be prevented from withdrawal from a block opening 2, the wall of the opening is provided with pockets thereby forming locking 65 knobs or enlargements on the bar 3. In Fig. 1 the depressions 4 are formed in each block at the ends of the holes 2 so that a part of each pocket or depression 4 is formed by adjoining blocks.

In Figs. 3, 4 and 5 the blocks are designated 5 and the enlargements on the binding-bar 6 extending therethrough are in the form of dove tails 7 formed in a side of each block, such dove tails filling recesses 75 8 of corresponding shape provided preferably throughout the width of the block transversely of the block opening 9 and in intersecting relation thereto as illustrated.

It is evident that my invention provides 80 a simple and efficient means for securing a plurality of blocks together in a rigid and durable manner, and that it renders a separation of the blocks and a changing or transposition of the same without detection 85 extremely difficult.

I wish it understood that my invention is not limited to any specific construction, arrangement or form of the parts, as it is capable of numerous modifications and 90 changes without departing from the spirit of the claims.

Having thus described my invention, what I claim as new and desire to secure by Letters Patent is,—

1. In combination, a plurality of blocks placed side by side in abutting relation and having registering openings therethrough with an opening of each block provided with a transversely extending enlargement at an 100 end thereof with the side walls of the enlargement recessed, and a binding material filling the openings and enlargements of the blocks to rigidly unite the same, the binding material being entirely enclosed by the blocks except at its ends.

2. In combination, a plurality of por-

celain blocks placed side by side in abutting relation and each having a recess in an abutting side wall thereof, which recess has the greatest width remote from the side of the 5 block in which it is formed, said blocks also having openings therethrough which register with each other and with the recesses,

said openings and recesses being filled with a binding material to rigidly unite the blocks in abutting relation.

In testimony whereof, I have hereunto signed my name to this specification.

HARRY W. FALCONER.
